SINGLE-ROLL GRINDING MILL

Oscar Soder, Niederlenz, Switzerland

Application January 21, 1933, Serial No. 652,884,
and in Germany February 2, 1932

5 Claims. (Cl. 83—14)

This invention relates to single-roll grinding mills wherein a roll cooperates with a counter member secured on a swingable carrier member and urged against the roll, through an intervening lever system, by means of a weight displaceably arranged on a lever arm.

Heretofore, in mills of this type, the lever arm carrying the weight was inclined to the horizontal which inclination varied with the wear on the counter member increasing. Due to this variation of the inclination of the lever arm the grinding pressure between the counter member and the grinding roll is also changeable, so that with such an arrangement it is necessary to 10 readjust the weight along the length of the lever arm for obtaining the same grinding pressure with different inclinations of this arm. Furthermore, with this construction it is impossible to read off the magnitude of the grinding pressure with the aid of a scale on the lever arm, as the divisions of the scale could only be adapted to a certain inclination of the lever arm and with any other inclination the indications of the scale were erroneous. Therefore, as with 15 the known mills of this type the adjustment of a constant grinding pressure of an exact predetermined magnitude is impossible the known mills were incapable of yielding a product of a certain fineness of grinding and consequently were not 20 precision devices.

According to the invention these drawbacks are eliminated in the mill by providing an extensible intermediate member for engaging the outer end of the carrier arm in a disposition 25 approximately perpendicular to said arm and connected to the lever arm carrying the weight, the arrangement being such, that the said lever arm is adapted to be set with respect to a control stop member in substantially horizontal 30 position by adjusting the intermediate member. This arrangement permits that in any condition of wear of the counter member the lever arm carrying the weight can be adjusted to occupy a horizontal position by adjusting the intermediate 35 member. In this manner, by displacing the weight along a scale on the lever arm, a certain grinding pressure can be invariably set and controlled at any time.

This device is particularly advantageous for 40 mills wherein, by subdividing the counter member, several sections are formed, as in such mills each counter member of the various sections is differently loaded and separately adjusted. Thus with the mill, according to the invention, 45 by shifting the weight along the scale on the

lever arm, the grinding pressure can be very quickly set to the required value in every section of the mill and controlled at any time.

In the accompanying drawings a constructional form of the invention is illustrated by way 60 of example only, in which

Fig. 1 shows an elevation of a single-roll mill.

Fig. 2 is a cross section of the mill.

Fig. 3 is a view of a detail of Fig. 1 on a larger scale, and

Fig. 4 is a section on the line III—III in Fig. 3.

Referring to the drawings, 1 represents the grinding roll, 2 the counter member and 3 the grinding space which tapers in the direction of rotation of the roll. By subdividing the counter member, several sections of the mill are formed and disposed side by side. In Fig. 1 only the first and last sections are completely shown, as indicated by the double chain dotted line. The grinding roll 1, which may be common to all sections, is mounted on a shaft 4 which is actuated by means of a pulley 5.

Each counter member is pivotally arranged on a pin 7 fastened to a carrier arm 6 and can be fixed thereon by tightening the nuts 8 of the pin in different positions of adjustment relatively to the grinding roll. For assisting in adjusting the grinding space 3, by means of the counter member 2, a set screw 9 is provided on the carrier arm 6. The carrier arms 6 are linked with their lower ends to a shaft 11 mounted in bearings 10. The forked upper ends 6' of the carrier arms are provided with incisions for receiving lateral bearing studs of a crosshead 12. The crosshead 12 is mounted on an adjusting sleeve 13 provided with a control disc 14 and screwed on a rod 15, so as to be adjustable on the rod 15 by correspondingly turning the disc 14, the cross head being engaged by shoulders on the adjusting sleeve for coupling these two parts for common movement. The rod 15 is pivotally connected to a crank arm 16 which is secured on a pivot pin 17 which is mounted in a bearing support 18 and fixed with its other end to a lever arm 19 (Fig. 4). On the lever arm 19 a weight 20 is displaceably arranged and

adapted to cooperate, by means of a handle piece 20', with notches 21 for definite adjustment into different positions on the lever arm 19. By action of the weight 20 the counter member 2 is pressed against the grinding roll 1 through the intermediary of pivot pin 17, rod 15, arm 16, and carrier arm 6 the magnitude of this pressure being regulatable by shifting the weight 20 on the lever arm 19. To a projection 18' on the bearing support 18 a carrier bar 22 is secured

through the end of which a set screw 23 is screwed which serves for supporting the lever arm 19, when the feed of stock material is discontinued. The lever arm 19 is rearwardly prolonged beyond 5 its fulcrum to project with an arm 19' into the interior of the casing 24 of the machine, where it is provided with a bearing face which cooperates with a cam disc 25 on a shaft 25'. By turning a hand crank 26 connected to the end of the 10 shaft 25', cam disc 25, lever arm 19 and the weight 20 together with it can be raised for retracting the counter member 2 from the grinding roll 1. The lever arm 19 is thus held in the raised position by the cam 25 with the grinding 15 member relieved from the influence of the counter weight.

Above the grinding space 3 of each section of the mill, a pair of auxiliary rolls 27, 28 for coarse comminution of the goods that are admitted to 20 them by feed rolls 30, 31 is arranged. The roll 28 has its bearings in a housing 32 which is linked to the casing 24 by means of a shaft 33. A screw spindle 36 provided with a hand wheel 35 and threadedly connected to a stirrup 38 which 25 is swingably arranged on a pin 37, is adapted to exert pressure on a projection 34 on the housing 32. In this manner the grinding pressure between the rolls 27, 28 can be adjusted by means of the hand wheel 35. The stationary rolls 27 30 are carried by a common shaft 39 which is driven from the main drive shaft by means of a belt drive including the pulleys 40 and 41. The adjustable rolls 28 partake of the rotational movement by action of the grinding pressure. As to 35 each mill section a separate pair of rolls 27, 28 is correlated and one roll of each pair is accommodated in a separate housing, the grinding pressure between every pair can be set for each mill section separately and independently of the other 40 sections to any desired value. This is of particular advantage, when through the same mill a larger number of portions of the same amount of stock material are fed in parallel. On the other hand it is obvious that the mill is also 45 adapted for passing separate stock materials through each section.

The goods precommminuted by the pair of rolls 27, 28 of a mill section drops directly into the grinding space 3 between the roll 1 and the counter member 2 beneath. Thus provision is made 50 that the coarse comminution which requires a greater grinding pressure is effected along a line bearing between the pair of rolls 27, 28. Whilst between this pair the branny material is flattened 55 out, in the grinding space only a sizing of the bran particles takes place without a simultaneous grating effect. In this manner heat production in the grinding space is considerably diminished which also results in a saving of power consumption of 60 the mill.

The specific pressure arising between the counter member 2 and the grinding roll 1, which is characteristic for the fineness of grinding, can be read on a scale on the guide track of the lever arm 65 19. The divisions of this scale may be so chosen that reading off the absolute value of the specific pressure is rendered possible. With this arrangement for the counter weight the specific pressure remains constant even with fluctuations in the 70 feed of the material and expansions due to heat in the grinding elements arising.

As aforesaid the set screw 23 is so adjusted that the lever arm 19 bears against the same when the feed of stock is discontinued. Thereupon, the 75 grinding space 3 can be opened the maximum

amount or set for any desired sizing by means of the control disc 14, in such manner, that the grinding surfaces contact but slightly or not at all. A slight contact is most advantageous for a proper grinding operation and at the same time no detrimental effects are exercised on the grinding members, even when the mill is running idle, as with the feed to the mill ceasing the cooperating surfaces of these members are not rubbing each other. On the continuation of the feed the grinding pressure sets in automatically and immediately reassumes its predetermined value.

When it is intended to pass through the same mill several different stock material each of which requires a special grinding pressure, so that for example the first section is to be set to a pressure of 80 grams per square centimeter, the second section to 60 grams, the third section to 40 grams, and the fourth section to 70 grams and so forth, the counter weights can be readily adjusted to the respective positions and the pressure controlled any time.

By raising the rod 15, the bearing studs of the cross head 12 can be removed from the incisions of the carrier arm 6, whereafter the carrier arm 100 is adapted to be swung out of operative position together with the counter member 2 even during the run of the mill. The position of the counter member 2 relatively to the grinding roll 1 can be precisely adjusted by means of the set screw 9. 105 Aside from this, the counter member is readily exchangeable at any time by loosening the nuts 8 on the pin 7. Furthermore, the carrier arm is so mounted on the shaft 11 that it may be readily taken off the shaft without shifting the same.

By means of the hand crank 26 all the counter members 2 of the mill are adapted to be simultaneously released. On the other hand each counter member 2 is adapted to be separately rendered inoperative either by rotationally displacing the control disc 14 or by raising and temporarily locking the lever arm 19 carrying the weight 20 in the thus retracted position.

The described device for setting the grinding pressure including the adjustable and retractible counter weight is applicable to any grinding mill comprising grating working faces, irrespective of the presence of means for coarse comminution.

I do not limit myself to the particular size, shape, number or arrangement of parts as shown and described, all of which may be varied without going beyond the scope of my invention as shown, described and claimed.

What I claim is:

1. In a grinding mill of the type described, in combination, a grinding roll, a counter grinding member for said grinding roll, a lever system connected with said counter grinding member, a lever arm of said system linked to the casing of the mill at the end of said system opposite to said grinding member, a control stop for said lever arm for supporting the same in a substantially horizontal disposition, a counterweight displaceably arranged on said lever arm for regulating the grinding pressure between said grinding roll and said counter grinding member, a pivotal carrier arm of said system for said counter grinding member, an extensible member intercalated between the outer end of said pivotal carrier arm and said lever arm and extending substantially perpendicularly to said carrier arm, and means for adjusting the length of said extensible member for setting said lever arm with the aid of said control stop into that predetermined substantially horizontal position which corresponds to the desired grinding pressure,

2. In a grinding mill of the type described in combination, a grinding roll, a counter grinding member for said grinding roll, a lever system connected with said counter grinding member, a lever arm of said system linked to the casing of the mill at the end of said system opposite to said grinding member, a pivot secured to said lever arm, a crank arm secured to said pivot of said lever arm, a control stop for said lever arm for supporting the same in a substantially horizontal disposition, a counterweight displaceably arranged on said lever arm for regulating the grinding pressure between said grinding roll and said counter grinding member, a pivotal carrier arm of said system for said counter grinding member, an extensible member linked with one end to said crank arm and with the other end to the outer end of said pivotal carrier arm and extending substantially perpendicularly to said carrier arm, and means for adjusting the length of said extensible member for setting said lever arm with the aid of said control stop into that predetermined substantially horizontal position which corresponds to the desired grinding pressure. 60
3. In a grinding mill of the type described, in combination, a grinding roll, a counter grinding member for said grinding roll, a lever system connected with said counter grinding member, a lever arm of said system linked to the casing of the mill at the end of said system opposite to said grinding member, a pivot secured to said lever arm, a crank arm secured to said pivot of said lever arm, a control stop for said lever arm for supporting the same in a substantially horizontal disposition, a counter weight displaceably arranged on said lever arm for regulating the grinding pressure between said grinding roll and said counter grinding member, a pivotal carrier arm of said system for said counter grinding member, an extensible member intercalated between the outer end of said pivotal carrier arm and said lever arm and extending substantially perpendicularly to said carrier arm, and means for adjusting the length of said extensible member for setting said lever arm with the aid of said control stop into that predetermined substantially horizontal position which corresponds to the desired grinding pressure. 65
4. In a grinding mill of the type described, in combination, a grinding roll, a counter grinding member for said grinding roll, a lever system connected with said counter grinding member, a lever arm of said system linked to the casing of the mill at the end of said system opposite to said grinding member, a control stop for said lever arm for supporting the same in a substantially horizontal disposition, a counterweight displaceably arranged on said lever arm for regulating the grinding pressure between said grinding roll and said counter grinding member, a rearward arm of said lever arm projecting beyond the fulcrum of the latter, a cam disc cooperating with said rearward arm of said lever arm for raising the latter and holding the same with the counter grinding member relieved from the influence of said counterweight, a pivotal carrier arm of said system for said counter grinding member, an extensible member intercalated between the outer end of said pivotal carrier arm and said lever arm and extending substantially perpendicularly to said carrier arm, and means for adjusting the length of said extensible member for setting said lever arm with the aid of said control stop into that predetermined substantially horizontal position which corresponds to the desired grinding pressure. 70
5. In a grinding mill of the type described, in combination, a grinding roll, a counter grinding member for said grinding roll, a lever system connected with said counter grinding member, a lever arm of said system linked to the casing of the mill at the end of said system opposite to said grinding member, a control stop for said lever arm for supporting the same in a substantially horizontal disposition, a counterweight displaceably arranged on said lever arm for regulating the grinding pressure between said grinding roll and said counter grinding member, a pivotal carrier arm of said system for said counter grinding member, a rotatable part of said extensible member threadedly connected to the other end of its body, a crosshead mounted for rotation on said rotatable member, lateral bearing studs provided on said crosshead for engagement in said slotted outer end of said carrier arm in a substantially perpendicular disposition to said carrier arm, and coupling means arranged between said crosshead and said rotatable member for common shifting movement of these parts on the body of said extensible member on rotational displacement of said rotatable member for adjusting the length of said extensible member for setting said lever arm with the aid of said control stop into that predetermined substantially horizontal position which corresponds to the desired grinding pressure. 75
